(57) **CLAIM**

I claim the ornamental design for a photo visor organizer, as shown and described.

DESCRIPTION

FIG. 1 is a front view of a photo visor organizer, showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken line showing of the visor is included for the purpose of illustrating environmental structure and forms no part of the claimed design.
